WILLIAM E. PRICE

BY
Morris Finkstein
ATTORNEY

UNITED STATES PATENT OFFICE.

WILLIAM E. PRICE, OF HARTSDALE, NEW YORK.

THEATRICAL STAGE.

Application filed October 7, 1922. Serial No. 592,933.

To all whom it may concern:

Be it known that WILLIAM E. PRICE, citizen of the United States, residing at Hartsdale, in the county of Westchester and State 5 of New York, has invented certain new and useful Improvements in Theatrical Stages, of which the following is a specification.

This invention relates to theatrical stages, scene hangers for theatre prosceniums and 10 particularly to that type which is collapsible for the purpose of transportation.

One of the objects of this invention is the provision of an easily assembled, rigid and strong, though readily collapsible framework, 15 on which any desired stage equipment, such as lighting devices, curtains, drops, wings, flats, borders, and the like may be supported.

A further object of this invention is the 20 provision of a complete portable scenery frame, adjustable to any size within the limits of the device, and capable of being set up in any suitable space, such as in the open air, on a larger platform, in a church or 25 other place where it may be desired to give a public or private entertainment such as a hall or lecture room, and where permanent stage accessories are too cumbersome, expensive or unsightly to maintain.

30 Other objects of this invention will in part be obvious and in part hereinafter pointed out.

The invention accordingly consists in the 35 features of construction, combinations of elements and arrangement of parts which will be exemplified in the construction herein-after described and of which the scope of invention will be indicated in the following claims.

40 In the accompanying drawings, in which is shown one of various possible illustrative embodiments of this invention,

Fig. 1 is a front elevational view of a support or framework embodying my invention 45 showing the lights and wings in place;

Fig. 2 is a side elevational view and partial vertical section taken on the line 2—2 of Fig. 1;

Fig. 3 is a partial vertical section and 50 front view of a portion of the support, showing the means for supporting one of the drops;

Fig. 4 is a front view of my improved clamping unit showing the same adapted for

use in connection with a frame member of 55 small diameter;

Fig. 5 is a similar view of the same as it appears adjusted to a frame member of larger diameter; and

Fig. 6 is a cross-sectional view of the coupling member adjustably connecting the parts of each of the diagonal braces of the frame.

In the illustrated embodiment of my invention, I employ preferably hollow, cylindrical, pipe members for the various parts of the frame, for the purpose of strength and lightness and for ease in adjustment, collapsibility and assembly. The corner uprights or posts 10 of the frame are suitably 60 mounted in the bases 11, and are extensible by reason of the extension member 12, which is capable of being fastened to the main portion of the upright by means of the reducing nipple 13 fastened to the member 10, and the set screw 14. All of the extensible members of the frame have similar extension members, reducing nipples and set screws for adjusting said members to the 65 desired length.

The clamping unit (see Figs. 4 and 5) for adjustably and removably connecting the extension 12 to the horizontal front and rear top members, and for connecting the various other members together, will now be described.

Said clamping unit comprises the gripping members 15 and 16, connected by means of the bolt 17 and the thumb nut 18 at the end of said bolt, which is secured to the member 15 substantially at right angles thereto and near the ends of said gripping members by means such as a pin 19. One extremity 20 of the member 15 may be 70 removably pivoted to the cross arm 22 of the T-shaped member 16 by means of the bolt 21 passing through any one of the apertures 23, 24, 25 or 26 of the arm 22, depending on the diameter of the cylindrical member to which said clamping unit is to be attached. The other extremity of the member 15 terminates in a nut 27 threaded to receive the threaded end 28 of one of the frame members, while the inner surface of the V-shaped member 15 is serrated to form the teeth 29, a portion 30 between said teeth substantially 75 at the point of the V being left comparatively smooth for the purpose of receiving

the frame members of small diameter (such as 31) as shown in Fig. 4. On one side of the gripping portion of the member 16 are formed the teeth 32, adapted to engage 5 frame members such as 33 of comparatively large diameters, as shown in Fig. 5, while the opposite side of said gripping member 16 is notched to form a pair of gripping teeth 34 for the purpose of engaging frame 10 members 31 of small diameter as shown in Fig. 4. A suitable slot 16' is made in the extremity of the gripping portion of the member 16 for allowing the removal of the bolt 17 therefrom without entirely removing 15 the nut 18 from said bolt, the member 15 pivoting about the bolt 21 in the removal operation.

It will be seen that this clamping unit may be used to connect the frame members together at any point of one of said members, 20 and at any angle, as where diagonal cross braces are fastened to the horizontal and vertical members of the frame. It will be seen further that attachment and removal 25 of the clamps may be quickly and easily effected.

Hereinafter, wherever a clamping unit or clamp is mentioned, a unit of the type above described is preferably to be used. Continuing with the description of the frame, 30 the extension member 12 is threaded into the nut member 27 of the clamping unit 35, in which is gripped the front top horizontal member 36 at any desired point thereof. Said top member 36 may be supported by 35 means of a clamping unit 38 removably fastened to a suitable bracket 37 secured to the stage wall, said clamping unit being screwed into the extension member 39 of the top 40 front member 36. My improved frame is substantially symmetrical on each side of the center line thereof, and a description of one side will, therefore, suffice for both.

The clamping units 41, removably attached 45 to the front top bar 36, are used to secure the rearwardly extending extensible members 40 to said bar 36 substantially at right angles thereto. Within reach from the floor is disposed a rearwardly extending and extensible bar 42 suitably secured to one of each of the front and rear uprights 10 by 50 means of the clamping units 43. The extensible portion 44 of said bar is connected to the main portion 44 by means of the reducing nipples 45 and set screw 46 similar to nipple 13 and set screw 14. A suitable cleat 47 is provided on said bar 42 whereon control ropes, wires, or cables may be fastened, when desired.

For bracing the frame against sway in any direction, suitable collapsible, removable braces, disposed diagonally of the other frame members, are provided. The rear extensible brace 48 is secured at the rear of 60 the frame-work to the uprights 10 by means

of the clamping units 49 and 50 combined with suitable pipe elbows, near the upper and lower ends respectively of the rear uprights. Said brace 48 comprises two portions 48' of substantially the same diameter 70 and suitably secured together, as by means of a coupling 51 (Fig. 6) having a pair of cylindrical openings therein through which said portions 48' are adapted to pass, set screws as 52 being provided to removably 75 fasten the parts of the brace together in the required positions thereof. Similar removable and adjustable corner braces 53, connected to a front upright post 10 by the clamp 55 and a suitable elbow, and connected to the top front bar 36 by the clamp 56 and another elbow, serve to maintain the parts in position, and to brace the frame against certain of the stresses therein, while cross braces 54 and 57 extending from the rear to the front uprights, serve similarly to prevent movement or collapse rearwardly or forwardly.

A lower extensible front bar 36' is substituted instead of a diagonal brace at the front of the frame, and is secured to the two front uprights 10 by means of the clamps 38'. The top front bar 36 is trussed by means of the collapsible tie-rod 58, having the turnbuckle 59 arranged thereon for adjusting said tie-rod to the various lengths to which said bar may be extended. Clamping units 60 serve to removably and adjustably connect the ends of the rod 58 to said bar 36.

Having described the main framework, I will now describe the means for hanging thereon and for manipulating the various wings, drops, curtains and lighting devices usually employed on a stage for producing the desired scenic effects. Each of the rearwardly directed frame members 40 has a plurality of bearings 61 thereon, spaced as closely together as may be demanded by the varied requirements of stage setting. A suitable pulley such as 62 is revolvably mounted in each of said bearings (Fig. 3). The flexible connection 63, of rope, wire or cable, passes over the pulley and is fastened by means of the portions 63' thereof to the extensible bar 64. Said bar 64 has adjustable extensions 65 thereon, removably secured to the main bar 64 by means of the reducing nipples 66 and the set screws 67, the end of the connecting cable 63 being hitched to the cleat 47 of the bar 42, when the bar 64 has been raised or lowered to the required height. On the bar 64 is attached the curtain drop or other scenery, the scene being shifted in the usual manner by raising the bar 64, said scene being set into place by merely lowering said bar through the cable 63. To one of the bars 64 may be hung the lighting and reflecting device 68, as by means of the clamps 69, said device 68 being ad-

justed into position by securing the clamps 69 at the proper point on the bar 64. Side reflectors as 70 may be positioned at any point along the posts 10 by means of the 5 clamps 71.

When a quick change of scenery is desired, the side wings 72, which may have different scenes painted on the sides thereof, may be quickly reversed to expose the new 10 scene on the back thereof. The means by which this is accomplished includes the pulley 73 which is revolvably mounted on the substantially vertical stud 74. Said stud is connected to one of the bars 40 by means of 15 the clamp 75, the wing 72 being secured to the pulley as by means of the bar 77 and a suitable T, the pulley being turned by means of a suitable flexible connection 76 of rope, wire or cable. Said wings 72 may be used to 20 provide exits and entrances in the usual manner, though exit doors may be made in the scenery if desired.

It will thus be seen that the various parts 25 of my improved frame may be quickly and easily put together and taken apart, that it is adjustable to a great variety of sizes, that it is capable of supporting a sufficient number 30 of scenes and lighting devices for a complete performance so as to provide a complete stage and setting, and that it occupies little space when collapsed and is therefore readily portable.

It will thus be seen that there is provided 35 a device in which the several objects of this invention are achieved and which is well adapted to meet the conditions of practical use.

As various possible embodiments might 40 be made of the above invention and as various changes might be made in the embodiment above set forth, it is to be understood that all matter herein set forth or shown in the accompanying drawings is to be interpreted as illustrative and not in a limiting 45 sense.

Having thus described my invention, I claim as new and desire to secure by Letters Patent:—

1. In a portable scenery frame adjustable 50 to various sizes of length, width and height, cylindrical members, and means for removably securing said members together comprising a V-shaped gripping member, a T-shaped gripping member, means for reversibly pivoting said T-shaped member to one 55 end of the V-shaped member to accommodate cylindrical members of various diameters, teeth in both of said gripping members adapted to engage one of the cylindrical 60 members, and a single tightening means at the other end of said V-shaped member.

2. In a demountable portable stage scenery frame having upright and horizontal connecting members, clamping means for removably fastening said connecting mem-

bers together comprising a pair of pivoted gripping jaws adapted to be secured to one of said connecting members, and single screw means to tighten said jaws, one of said jaw members having a plurality of fixedly spaced 70 pivoting points thereon for adjustment of said clamping means to accommodate connecting members of various thickness.

3. In a demountable portable stage scenery frame having upright and horizontal 75 connecting members, clamping means for removably fastening said connecting members together comprising a V-shaped gripping member, means on one end of said V-shaped member for mounting on said connecting member, a T-shaped gripping member pivoted to the other end of said V-shaped member, teeth in both of said gripping members adapted to engage one of the connecting 80 members, and a single means for tightening the clamping means, said T-shaped member having a plurality of pivoting points thereon arranged to co-act with said V-shaped member in reversed side relationship for adjustment of said clamping means to accommodate connecting members of various thickness.

4. An extensible stage frame pipe member comprising an elongated central tubular portion uniform in diameter, tubular end 95 portions adjustably telescoping in said central portion, each end portion being substantially shorter and less in diameter than said central portion, and attaching means on each of said end portions for engaging with other 100 frame members.

5. An extensible securing frame adapted to form a portable stage comprising corner uprights and rigid horizontal connecting members arranged along the length and width of the frame, each of the uprights and members having a central portion of substantially uniform diameter, end portions adjustably telescoping in said central portions, and clamping means terminating said 105 end portions constructed to removably connect with either central or end portions of other frame members.

6. An extensible scenery frame adapted to 115 form a portable stage, comprising corner uprights rigid horizontal connecting members arranged along the length and width, and a depending scene supporting bar, each of the upright members and bar having a central portion of substantially uniform diameter, end portions adjustably telescoping in said central portions, and clamping means terminating in said end portions constructed to removably connect with either central or end portions of other frame members, and means adjustable along said members for raising and lowering said bars.

In testimony whereof I affix my signature.

WILLIAM E. PRICE.
